UNITED STATES PATENT OFFICE.

MATTHEW M. DODD, OF PORTSMOUTH, VIRGINIA, ASSIGNOR TO THE AUTOMATIC TRACK-SANDING COMPANY, OF MAINE.

AUTOMATIC TRACK-SANDING APPARATUS.

SPECIFICATION forming part of Letters Patent No. 518,715, dated April 24, 1894.

Application filed March 30, 1893. Serial No. 468,392. (No model.)

To all whom it may concern.

Be it known that I, MATTHEW M. DODD, a citizen of the United States, residing at Portsmouth, in the county of Norfolk and State of Virginia, have invented certain new and useful Improvements in Automatic Track-Sanding Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in automatic track sanding apparatus, and it has for its objects among others to provide a simple and cheap attachment to the air brakes now in use where-
20 by air will be automatically supplied to the sanding apparatus.

It is a well-known fact that it is now obligatory upon the engineers upon nearly all of the railroad lines throughout the country 25 to apply sand to the tracks at the same time or immediately before the brakes are applied in order to prevent the wheels from sliding or skidding. Heretofore, it has been the practice, so far as I am aware, to have the parts 30 so constructed and arranged that the act of supplying the sand has been independent of that of applying the brakes, that is, it has required the turning of an independent lever, such as the opening of a globe or other valve 35 by hand. It often happens that the engineer will forget or neglect to close this valve after having opened it to permit of the flow of the sand and the consequence is that he thereby loses the greater portion of the sand in the 40 sand box without deriving any benefit therefrom.

The main object of my present invention is to so construct and arrange the parts that the sand will be supplied automatically or 45 immediately before the brakes are applied. I connect a pipe with the air brake in such a way that when the valve handle is turned to apply the brakes and when it reaches what is known as a "lap" air is supplied to the 50 sanding apparatus. My device brings the

main reservoir in communication with the said pipe every time the brakes are applied. The air supply is shut off as the lever is turned to take off the brakes.

My improvements are applicable to air 55 brakes now in use. It is shown in connection with the air braké and sanding device of Leach, but is applicable to other forms. It adds but little to the cost of the sanding apparatus and can be readily applied without 60 any material change in the structure thereof.

Other objects and advantages of the invention will hereinafter appear and the novel features thereof will be specifically defined by the appended claims. 65

The invention is clearly illustrated in the accompanying drawings, which, with the letters of reference marked thereon, form a part of this specification, and in which—

Figure 1 is a sectional view showing my 70 improvements. Fig. 2 is a perspective view of the brake lever, key and cap-nut removed.

Like letters of reference indicate like parts in both of the views where they appear.

As my present invention has no relation 75 to the peculiar construction and arrangement of the parts of the sanding apparatus of the peculiar character of the air brake other than will be hereinafter explained I have shown only such parts as are intimately connected 80 with my invention.

Only such parts of the brake mechanism as co-operate with my improvements will be described.

Referring then to the details of the draw- 85 ings by letter, A designates the valve and A' the connection with the main reservoir.

B is the key and C the cap nut. The space between the top of the valve and the under side of the key is always open to the main 90 reservoir.

D is a small pipe connected at one end with the cap nut C and at the other end with the pipe E which is the pipe now employed running from the main reservoir to the sand box, not shown. In my construction I dispense with the globe valve, usually located in the pipe E usually at about the point e and manipulated by hand by the engineer to supply air to the sanding apparatus. 95 100

F is a valve integral with the key and provided with a port *f* through it which is brought into open communication with the pipe D when the engineer moves the handle *a* of his valve to apply the brakes and when the handle reaches what is known as "on lap" and is closed when the handle is moved in the opposite direction to release them. This obviates the necessity of the engineer having to manipulate the globe valve hereinbefore referred to each time he applies the brakes and closing it when he releases them. The valve is actuated to admit air to the sanding box each time the brake lever handle 15 is operated and by the same movement; this makes one less movement for the engineer and one less thing for him to remember. It will be understood that the port in the valve which is integral with and moves with the 20 key is brought into communication with the oblong port *d* in the cap-nut which communicates with the pipe D each time the handle is turned to apply the brakes as soon as the handle reaches what is known as on lap and 25 as positively cut off when the handle is turned to release them.

In order that the sand may be applied to the tracks immediately before the brakes are applied, I make the port *d* in the cap-nut of 30 such length as to permit the air to pass through the said port to the pipe D, during the forward movement of the handle of the brake valve, and before the said handle has been moved a sufficient distance to apply the 35 brakes.

Modifications in detail may be resorted to without departing from the spirit of the invention or sacrificing any of its advantages.

What I claim as new is—

40 1. The combination of the engineer's brake valve, a key carrying the valve for supplying air to the track sanding apparatus, and the engineer's lever *a*, all adapted to be moved around the same vertical axis, and the said 45 valve for supplying air to the track sanding apparatus being within the same housing as the engineer's valve, substantially as and for the purpose specified.

2. The combination with the engineer's 50 brake valve, a lever for operating said valve, and a key having a valve integral therewith for supplying air to the brake sanding appa-

ratus, the said two valves being inclosed in one case, substantially as specified.

3. The combination with the engineer's 55 brake valve, the lever for operating said valve and the part B interposed between the said operating lever and said engineer's valve, and not only serving as a key between the two, but also containing an opening *f* for automatically 60 supplying air to the sanding apparatus, substantially as shown and described.

4. The combination with the brake valve lever and the key for operating the brake-valve, of a cap nut, a pipe connected with the 65 cap nut, and a valve integral with the key, whereby air is automatically supplied to said pipe by the movement of the said lever, as and for the purpose specified.

5. The combination with the air brake valve 70 lever, a key for operating the brake valve having a valve integral therewith for supplying air to the track sanding apparatus, of a pipe for supplying air to the sand box, the said valve for supplying air to the sanding apparatus being 75 operated by the brake valve lever to admit air to the said pipe, substantially as set forth.

6. The combination with the brake-valve lever, a key for operating the brake valve and 80 the valve for supplying air to the track sanding apparatus, integral with the said key, and the cap-nut, of a pipe connected with the cap nut whereby air is automatically supplied to the said pipe by the movement of the said lever, as and for the purpose specified.

7. The combination with the engineer's 85 brake valve and the lever *a* for actuating the same, of a valve between said engineer's brake valve and said engineer's valve lever, adapted 90 to supply air to the track-sanding apparatus which intermediate valve for supplying air to the track sanding apparatus is integral with the key B, between the engineer's lever and the engineer's brake valve A, and connects 95 the cavity of the casing of the engineer's valve with the track sanding apparatus, substantially as shown and described.

In testimony whereof I affix my signature in presence of two witnesses.
